Patent expires April 13, 1963

4 Claims. (Cl. 122—406)

1

When the liquid and gaseous phases of a substance are in equilibrium inside a container, any lowering of pressure at a point inside the liquid which is not overcome by the head of liquid above the corresponding point, causes the appearance of the phenomenon of "cavitation." The latter is apparent in particular at the inlet of down-comers in steam boilers, and the bubbles of steam which are generated, accumulated in the vicinity of said inlet or driven by the liquid flowing to said inlet oppose the downward movement of the water in circulation.

The above phenomenon is amplified, and its consequences aggravated:

Firstly, if the liquid is already emulsified before arriving in the vicinity of the downcomer inlet, that is to say if it is mixed with a substantial quantity of steam bubbles;

Secondly, if the downcomer inlet is disposed in such a way that the liquid penetrates into it with a downward movement, and if said inlet is immersed to a sufficiently small extent for the vertical movements which take place in the vicinity of said inlet to extend up to the surface of the liquid. In this latter case cavitation starts at the surface of the liquid and extends spontaneously to the whole central zone of the vortices, thus creating a direct communicating chimney between the gaseous phase in the boiler and the downcomer and causing the complete failure of the latter.

The occurrence of these cavitation phenomena, in a steam boiler, for example, prevents normal circulations of the water from being established and may be the cause of serious damage.

It is the object of the present application to provide a simple remedy for these disadvantages, this remedy being applicable, moreover, not only to downcomers of steam boilers, whether the boilers are to be manufactured or are already in service, but also to tubings conducting any kind of liquid out of a reservoir where this liquid is to be found near its boiling point.

According to this invention, I provide upstream with respect to the usual inlet port of the downcomer a suction chamber the inlet to which is entirely submerged in the liquid and the top part of which is cooled by any suitable means (injection of cold liquid, surface refrigeration, etc.). The inlet aperture of the chamber has a large cross-section disposed in such a way that the liquid before entering it has no substantial vertical velocity which is likely to start surface vertical movements. Shortly after its admission into the chamber the velocity of the liquid should

5 be at first ascendent or horizontal in such a way as to facilitate the discharge of steam bubbles or gas bubbles towards the top part of the chamber which thus forms a steam trap where these bubbles are condensed as they arrive. The liquid thus deemulsified and slightly cooled then moves downwards towards the port of the discharge piping.

The chamber may be completely submersed in the liquid or its top part may partially emerge in such a way as to form a siphon. Its inlet opening is generally, but not necessarily, at a lower level than that of the axis of the discharge port. In the case of a discharge pipe of small diameter the chamber may be constituted simply by a plunger tube which prolongs the outlet tube to the interior of the boiler; this plunger tube is flared at the inlet and has a high point or steam trap where the refrigeration which produces the condensation is carried out. If the discharge pipe is of large diameter the chamber may be constructed by means of a partition at its top section.

25 The following description with reference to the appended drawings given solely by way of examples will show how my invention may be carried out.

Fig. 1 is a sectional elevation on line I—I of Figure 2, the middle part of the drum being omitted.

Fig. 2 is a horizontal section on line II—II of Figure 1.

Fig. 3 is a cross-section taken along line III—III on Fig. 1.

35 Fig. 3a is an exploded perspective view illustrating the details of the joint between certain elements of the feed water system.

Fig. 4 is a cross-section, drawn on a larger scale, taken along line IV—IV on Fig. 2.

40 Fig. 5 is a longitudinal section taken along line V—V on Fig. 4.

Fig. 6 is a view analogous to Fig. 1, showing a modification.

45 Fig. 7 is a corresponding horizontal section analogous to Fig. 2.

Referring to Figs. 1 to 5, the reference character 1 denotes the body portion of a water and steam drum of a boiler, wherein in steam-generating tubes (not shown) open in the zone between aa and bb; cup-shaped end portions 2, 3 are secured to the ends of drum 1. Passing through end portion 2 are a pair of feed water pipes 4, 5 merging into a common trunk 6 which is then bifurcated into a pair of short sections 7, 8 having end flanges 9, 10; secured through

flanges 11, 12 thereon are a pair of feed water discharge pipes 13, 14 opening towards the bottom of the boiler body to discharge feed water into said boiler body. Squeezed between flanges 9, 11 and 10, 12 respectively are a pair of perforated diaphragms such as 11' (Fig. 3a) provided for the purpose of building an increased water pressure upstream.

Passing through the drum 1 in the neighborhood of the ends thereof are four water return pipes or downcomers 15, 16, 17, 18; all of them are similarly constructed so that one only need be described in detail; pipe 17, for instance, downwardly directed outside the boiler, is connected to the discharge port 17e bored in the wall of the boiler or drum 1. Instead of permitting the liquid issuing from the boiler to enter directly the downcoming pipe 17 through port 17e that would result in the above-mentioned disadvantages, a suction chamber covering the port 17e is arranged within the boiler upstream with respect to said port.

In the embodiment of Figs. 1 to 3, said chamber consists of a plunger tube connected to the original discharge port 17e and extending the downcomer 17 within the boiler. Said plunger tube or chamber 17f, for instance, includes, from the drum wall, a slightly ascending portion 17a, then a top part or bend 17b, forming a steam trap, which merges into a downwardly directed portion 17c with a downwardly opening flared end 17d. Said flared end 17d is the inlet aperture for the liquid into the suction chamber or tube 17f preceding the original discharge port 17e.

Said inlet end 17d is entirely situated below the liquid level in the boiler or drum 1, the downcomer 17 with the plunger tube 17f acted then as a siphon. Moreover portion 17c is directed to the right as seen in plan view, so that said flared end 17d is located within the end portion 3, i. e. away from 6b.

Branching off from feed water pipes 13, 14 at points upstream with reference to the perforated diaphragms 11', 12' between flanges 9, 11, 10, 12 are four small pipes 19, 20, 21, 22 which enter chambers 15f, 16f, 17f, 18f, respectively; pipe 21 for instance includes an end portion 21a, located in the bend 17b of chamber 17f that is to say near the top of said chamber; said portion has a closed end 23 and is formed with a double row of perforations 24 in its upper zone.

Owing to the foregoing arrangement, relatively cool feed water is injected at the high point of pipes such as 17f under a pressure which may amount, for instance to some hundreds of grams per sq. cm. and is built up by reason of the provision of perforated diaphragm in feed water discharge pipes; said relatively cool feed water condenses any steam carried along with water in return pipes 17.

It should be understood that the diaphragm is merely an example of means to build up an increased pressure in the main feed water pipe, and obviously other known means providing a restriction in said main pipe upstream with respect to its discharge end may likewise be resorted to.

Referring to Figs. 6 and 7, wherein like parts are denoted by like reference characters, a downcoming pipe 25 is shown secured to end portions 2 and a partition 26 supported in the boiler drum 1 extends from the top thereof to a point substantially above the bottom, forming with the end portion 2 a trap for steam bubbles and leaving an inlet opening 27 which has a sufficiently large cross-section, in such a way that water passing 75

into the chamber 28 between said partition 26 and end portion 2 moves substantially horizontally. Passing through the wall of end portion 2 is a rising feed water pipe 29 which opens into a horizontal tube 30 closed at both ends and perforated in its upper portion. Hanging from end portion 2 above tube 30 is a bell-shaped member 31 shown as comprised by a semi-cylindrical sheet metal with end cheeks.

Any steam carried along with water past opening 27 and into the trap between the end portion 2 and partition 26 is condensed by relatively cool feed water from tube 30.

While I have described and illustrated specific embodiments which are believed to be efficient and reliable, my invention is not restricted thereto and many modifications may be brought about without departing from the spirit of this invention as comprehended by the following claims. The term boiler shall be construed broadly as meaning any vessel or reservoir containing a boiling liquid.

What I claim is:

1. The combination of a vapor-and-liquid boiler body for containing a liquid to be heated, an aperture provided in the wall of said boiler body through which liquid contained in the boiler body may be withdrawn, an external downcomer communicating with said aperture for receiving liquid withdrawn through said aperture, a steam trap chamber formed within said boiler body, said chamber having three openings therein, one of which is said aperture, the second of said openings being adjacent to the bottom of said boiler body and beneath the level of the liquid contained in said boiler body, a portion of said chamber extending upwardly to a point above both said aperture and said second opening, and means extending through said third opening and positioned in the said upwardly extending portion of said chamber for cooling the liquid which enters said chamber, whereby vapor in the liquid entering said chamber is condensed and liquid only is withdrawn through said aperture.

2. The combination of a vapor-and-liquid boiler body for containing a liquid to be heated,

a feed liquid supply pipe opening into said body, an aperture provided in the wall of said boiler body through which liquid contained in the boiler body may be withdrawn, an external downcomer communicating with said aperture for receiving liquid withdrawn through said aperture, a steam trap chamber formed within said boiler body, said chamber having three openings therein, one of which is said aperture, the second of

said openings being adjacent to the bottom of

said boiler body and beneath the level of the liquid contained in said boiler body, a portion of said chamber extending upwardly to a point above both said aperture and said second opening, and means extending through said third opening and positioned in the said upwardly extending portion of said chamber for cooling the liquid which enters said chamber, comprising piping extending from said feed liquid supply pipe to the upwardly

extending portion of said chamber whereby vapor

in the liquid entering said chamber is condensed and liquid only is withdrawn through said aperture.

3. The combination of a vapor-and-liquid boiler body for containing a liquid to be heated, a feed liquid supply pipe opening into said boiler body, an aperture provided in the wall of said boiler body, a downcomer extending thru said aperture into the boiler body and terminating

adjacent to the bottom wall of said boiler body and below said aperture and the level of the liquid contained in said boiler body, the portion of said downcomer within said boiler body having an intermediate section positioned at a point above said aperture to form a vapor trap, and piping extending from said feed liquid supply pipe to said intermediate section, whereby vapor in the heated liquid passing through said intermediate section is condensed by the cooler liquid supply introduced into said intermediate section through 10 said last named piping.

4. The combination of a vapor-and-liquid boiler body for containing a liquid to be heated, said boiler body consisting of a body portion and 15 two end portions, an aperture provided in one of said end portions toward the bottom thereof through which liquid contained in said boiler body may be withdrawn therefrom, a downcomer communicating with said aperture to receive the 20 liquid withdrawn therethrough, a partition within said boiler body separating the upper sections of said one end portion and said body portion to form a vapor trap in said one end portion, the lower sections of said one end portion and said body portion being in communication with one another through an opening provided in the lower 25 section of said partition beneath the level of the

liquid contained in said boiler body but not beneath said aperture, and means positioned in the upper section of said one end portion for cooling the liquid entering said one end portion, whereby vapor in the liquid which enters said one end portion is condensed and liquid only is withdrawn through said aperture into said downcomer.
